ATTORNEYS

UNITED STATES PATENT OFFICE.

ALBERT T. BROCH, OF NEW YORK, N. Y.

GAS HEATER.

Application filed November 3, 1922. Serial No. 598,859.

To all whom it may concern:

Be it known that I, ALBERT T. BROCH, a subject of the King of Norway, and a resident of the city of New York, borough of Manhattan, in the county and State of New York, have invented a new and Improved Gas Heater, of which the following is a full, clear, and exact description.

This invention relates to a gas heater, designed to be an improvement over the gas heater disclosed in my copending application, Serial No. 520865, filed January 21, 1922, and entitled "Gas heater."

An object of the invention is to provide a heater which is considerably simplified in its construction and arrangement.

Another object is to provide a one-piece fixture including a burner chamber and a mixing chamber with a connecting conduit suitably dimensioned to provide for a generous supply and flow of gas.

A further object is to provide a mixing chamber so disposed and constructed that there will be no leakage of gas even at low pressures.

A still further object is to provide a burning chamber in which the flame will be properly spread in issuing therefrom so that the heat will more efficiently come in contact and be radiated by the type of radiating device disclosed in the above mentioned application.

Another object is to provide a gas nozzle very simply disposed with relation to the mixing chamber and co-operating with an air regulating sleeve whereby the nozzle may be effectively held in place and is capable of very simple and ready dismounting when desired.

The invention is illustrated in the drawings, of which—

Figure 1 is a side view of the device showing the reflector plate in sections.

Fig. 2 is a vertical section taken through the device.

Fig. 3 is a horizontal section taken on the line 3—3 of Fig. 2.

The form of the invention shown in the

drawings is a preferred form, although it is understood that modifications in the construction and arrangement of the parts and in the character of the materials used may be adopted without departing from the spirit of the invention.

As shown in the drawings, the invention includes an integral one-piece casting in which is formed a conduit 1, preferably square in cross section, at one end of which is a flared mixing chamber 2 and at the other end a larger flared burner chamber 3. The dimensions of the conduit 1 and the chambers 2 and 3 are such as to permit of the ready flow of a generous amount of gas therethrough. The intermediate portion of the conduit 1 is provided, preferably, with an integrally formed flange 4 which, as shown in Fig. 1, is adapted to grip the back plate 5 of the reflector casing 6 between itself and the upper end 7 of a base portion 8, the conduit 1 passing through an aperture in the upper end 7 and clamped in position by a set screw 9. It is my intention to dispose the casting in such position that the burner and mixing chambers are disposed vertically, the mixing chamber extending downwardly and the burner chamber extending upwardly on opposite sides of the base or pedestal 8. By disposing the mixing chamber 2 downwardly, any gas which may be introduced thereto through a nozzle 10 will more readily pass upward therethrough into the conduit 1, so that if the pressure of the gas should be low there would be very little tendency for the gas to leak outward, since the natural tendency of the gas is to escape upwardly, if possible. The mixing chamber 2 is surrounded by a sleeve 11 made of any suitable thin metal and bent to the form of the outer surface of the mixing chamber 2. This sleeve may be suitably ornamented, if desired, and serves as a means for hiding any roughness of the casting. The lower end of the sleeve is provided with inwardly extending sector portions or spring plates 12 and 13. These plates on their in-

ward faces are provided with a series of notches 14 which are designed to receive the outer edges of the sector portions 12 and 13. The plates 12 and 13 are provided with a series of notches 15 which are designed to receive the outer edges of the sector portions 12 and 13. These plates on their in-

ner ends are provided with curved edges such as 14. These curved edges are adapted to lie between a collar 15 on the nozzle 10 and a plate 16 properly closing the bottom of the burner chamber 2. This plate 16 is provided with two sector-shaped openings 17 and 18 which are adapted to be covered by the sector plates 12 and 13 attached to the sleeve 11 when this sleeve is moved around the mixing chamber, whereby the plates 12 and 13 and the openings 17 and 18 can be relatively adjusted to regulate the admixture of air in the mixing chamber with the gas coming from the nozzle 10. A slot 19 is formed in the plate 16 extending from one of the openings, such as 18, and the nozzle 10 lies with its stem 20 disposed in said slot. A collar 21 formed on said stem is adapted to lie above the plate 16 so that the plate 16 and the spring plates 12 and 13 are gripped between the collars 21 and 15. The resiliency of the plates 12 and 13 tend to hold the nozzle in position. The nozzle can be removed by turning the plates 12 and 13 until the opening 18 is fully uncovered, at which time the stem of the nozzle can be withdrawn from the slot 19 and then can be withdrawn from the mixing chamber 2 through this opening 18. This construction affords a ready means for assembling the nozzle and a simple arrangement for holding it firmly in place and for permitting its ready dismantling or removal from the mixing chamber. The sleeve 11 may be suitably and artistically ornamented or arranged to hide the plainness of the casting.

At the other end of the conduit 1 a large generous burner chamber 3 is provided, somewhat cup-shaped in form and having its upper edge notched, as indicated at 22. A spreader plate 23 rests on the upper edge of the burner chamber 3, and it is beneath the edges of the spreader plate 23 and through the notches 22 that the flame escapes from the burner chamber 3. The flame escapes from this chamber and heats a semispherical mantle 24 which is also provided with a hood 25 above it, in the manner described in my copending application. This mantle is also provided with apertures 26 and 27 through which the heat and gases may escape beneath the hood. The mantle is mounted on a threaded stem 28 and rests on a nut 29 disposed on said stem. This stem extends down through the burner chamber 3 and at its lower end is provided with a clamping nut 30, and is also provided with a nut 31 bearing against the spreader plate 23. This burner chamber is of generous dimensions, and the spreader plate covering it permits the flame to be spread out beneath the mantle 24. It is a very simple matter to dismantle this end of the heater, since by merely unscrewing the

nut on the stem 28 it can be withdrawn from its relation with the burner chamber 3 and the entire device disassembled in this simple manner.

What I claim is:—

1. A gas heater which includes a conduit to be disposed in a horizontal position, a dependent mixing chamber extending downwardly therefrom having a plate across the bottom thereof and having sector-shaped openings in said bottom plate, a sleeve surrounding said mixing chamber, inwardly extending sector-shaped spring plates on the lower end of said sleeve, and a nozzle extending into said mixing chamber and engaged by the inner ends of said spring plates to hold the nozzle in position. 75
2. A gas heater which includes a horizontally disposed conduit, a dependent mixing chamber at one end thereof having an apertured plate across its bottom, said plate having a slot formed in its central portion, said slot extending inwardly from the edge of one of said apertures, a gas nozzle to be disposed in said slot, and a pair of collars on said nozzle disposed on opposite sides of said plate to support the nozzle on said plate. 80
3. A gas heater which includes a horizontally disposed conduit, a dependent mixing chamber at one end thereof having an apertured plate across its bottom, said plate having a slot formed in its central portion, said slot extending inwardly from the edge of one of said apertures, a gas nozzle to be disposed in said slot, a pair of collars on said nozzle disposed on opposite sides of said plate to support the nozzle on said plate, and a sleeve surrounding said chamber having inwardly extending spring plates disposed across the bottom of said chamber, the ends of said plates engaging between the lower collar on the nozzle and the under surface of the plate to resiliently hold the nozzle in position. 95
4. A gas heater which includes a horizontally disposed conduit, a dependent mixing chamber at one end thereof having an apertured plate across its bottom, said plate having a slot formed in its central portion, said slot extending inwardly from the edge of one of said apertures, a gas nozzle to be disposed in said slot, a pair of collars on said nozzle disposed on opposite sides of said plate to support the nozzle on said plate, and a sleeve surrounding said chamber having inwardly extending spring plates disposed across the bottom of said chamber, the ends of said plates engaging between the lower collar on the nozzle and the under surface of the plate to resiliently hold the nozzle in position, said spring plates acting as means to adjustably regulate the amount of the apertures exposed to regulate the flow of gas. 100

5. A gas heater which includes a conduit to be disposed in a horizontal position, a burner chamber extending forwardly from one end thereof, said burner chamber being 5 cup shape and having its upper edge notched, a spreader plate disposed over the top of said chamber to force the flames to issue from the chamber between its under surface and the notched edge of the cham-

ber, a threaded stem passing through said chamber and said plate, a nut on the end of the stem beneath the chamber, a nut on the stem above the plate to hold the stem and plate together, said stem extending above the plate, and a curved mantle supported on 15 said stem over the plate to act as a radiator for the heat.

ALBERT T. BROCH.
